FIG. X.

UNITED STATES PATENT OFFICE.

HERALD P. ARNT, OF LAKEWOOD, OHIO, ASSIGNOR OF ONE-FOURTH TO CURT B. MULLER, OF CLEVELAND, OHIO.

WHEEL CONSTRUCTION.

Application filed June 23, 1921. Serial No. 479,787.

My invention relates to a wheel construction and more particularly to the spoke and felly connection of an all-metal wheel.

I am well aware that the prior art patented as well as practiced is well developed owing to the growing recognition that the popularity of the wooden wheel, at least for automobiles, is on the wane. An important reason for this is the constantly decreasing supply and therefore increasing cost of the wood, notably hickory best adapted for their manufacture. It is moreover now known that metal wheels may be constructed to have greater strength though less weight in a certain size of wheel.

Metal wheels necessarily comprise a hub, a felloe and connecting spokes. Tubular spokes have been proven to be entirely feasible and represent the type of spoke construction which I prefer. I have for some time been engaged in the manufacture of all-metal wheels, but am now convinced that the trade demand is for a wheel resembling as closely as possible the conventional design of a wooden wheel. The endeavor to satisfy this demand has however encountered problems of manufacture and assembly which for the first time have been solved after the manner of my series of inventions, one of which, the resulting structure, constitutes the subject matter of this application.

I realize that the scope of my invention comprehends many equivalent constructions. The showing of the drawings and the particular description are merely specific exemplifications of a plurality of mechanical embodiments and arrangements.

Adverting to the drawings:

Figure I is an enlarged partial elevation with one portion in section.

Figure II is a section on line II-II of Figure I.

Figure III is a section on line III-III of Figure I.

Figure IV is a section on line IV-IV of Figure I.

Figure V is a section on line V-V of Figure I.

Figure VI is a section on line VI-VI of Figure II.

Figure VII is a section on line VII-VII of Figure II.

Figure VIII is a section on line VIII-VIII of Figure II.

Figure IX is a section corresponding to

Figure V of a modified form of spoke adapted to wide wheels.

Figure X is another section of a modified form of spoke taken through a middle portion of it.

A hub 1 is fashioned with an annular flange 2 provided with six circumferentially arranged and equispaced holes 3. A felloe 4 adapted for the mounting of a composite or demountable rim structure, not shown because common to the art, is provided in its middle portion with twelve circumferentially arranged holes 5 bordered by outwardly directed flanges 5^a. Tubular spokes 6 tapered in a direction toward the felloe 4 have their outer ends 7 of reduced size to enable them to project through the outwardly flanged holes 5 respectively, preparatory to being expanded, spread, enlarged, or curled against the flanges 5^a at 8 so as to effect interlocked connections, or the spoke extremities may be spun over to enclose the flanges by extending across their annular extremities and contacting their outer sides as shown. It will be observed that the longitudinally curved, tapered exterior surface of each fillet or inclined shoulder 9, which is formed at the junction of the outer end of the middle portion 6 of the spoke with the reduced portion 5, forms a neat abutting seam with the rounded defining edge of one of the holes 5, the inner margins of which merge with the inner or concave side of the felloe. Such a fitting between the felloe and spoke affords a greater area of contact and provides greater strength. It also limits the encountered stress and resulting strains to a curved surface thereby avoiding the possibility of a metal fracture and the tendency of the reduced end of the spoke to telescope into its larger section, by reason of a distribution of the radial thrusts because the fitting yields during rocking or pivotal motion tendencies in various directions.

The inner or nave ends of the spoke are designed to simulate or resemble the conventional frustro-wedge shaped design of the corresponding end of a wooden spoke, being fashioned with one parallel pair of oppositely disposed flat sides 10 and another pair of centrally converging flat sides 11. The inner ends of the spokes abut the hub 1 while the radial sides 11 abut each other and for a considerable distance, indeed, to points

outwardly beyond the edge of the flange 2. As will be observed the outward divarication of the radial sides 11 continues until they span a space exceeding in width the greatest 5 diameter of the curved portion 6 of the spoke, from which points the sides 11 are curved toward each other to form shoulders 12 and then merge all around at 13 with the curved surfaces of the spokes.

10. Similar in shape to the flange 2 and co-operating to clamp in conjunction with it is a ring 14 fashioned with circumferentially arranged holes 15 correspondingly located as are the openings 3 so as to be adapted to 15 register therewith. Bolts 16 are then passed through the openings 3 and 15 and through certain of the spokes to be held in place by nuts 17.

It will be observed that the holes 5 in the 20 felloe are bordered by outwardly projecting annular flanges 5^a so that if the reduced outer end 7 of a spoke projects through one of the openings 5 and initially a suitable distance outwardly beyond the edge or rim of 25 the flange 5^a, the extremity of the spoke may be expanded, curled or spun over and inwardly around the rim of the flange. When this occurs, as will be readily understood by those skilled in the art, especially when the 30 nave extremity of the spoke is adequately supported and held against displacement from its proper radial axis, the spoke fillet, formed at the junction of the middle portion 6 with the smaller end 7, will be drawn 35 radially outward tightly against the inner annular surface of the felloe 4, thereby effecting a wedge fit and the desirably neat seam which may be readily concealed when the wheel is painted. Practice has however 40 demonstrated that notwithstanding the interlocked connection thus effected, an infinitesimal yielding or universal pivotal action therebetween is realized, tending to relieve excessive strains and reduce likelihood of incipient fracture.

I claim:—

1. In combination, a felloe provided with an outwardly flanged opening, a tubular spoke including a fillet adapted to wedge abut the inner margin of said opening, the outer end of said spoke occupying said opening and its extremity projecting outwardly beyond the extremity of said flange and curled around the latter to seat said fillet against the margin of the opening and to confine the extremity of the flange whereby to interlock the parts.

2. In a wheel, the combination of a felloe provided with an outwardly flanged opening, and a tubular spoke projected through said opening and having its outer extremity bent across the edge and against the outer side of said flange.

3. In a wheel structure, the combination 65 of a felloe provided with an outwardly

flanged opening, and a tubular spoke having a smaller outer end fitted in said flanged opening, the extremity of said spoke being curled entirely around the extremity of said flange whereby the spoke is locked against 70 perceptible movement radially in either direction.

4. In a wheel structure, the combination of an annular felloe provided with a round opening the edge of which is also rounded to progressively larger diameter toward the concave side of the felloe, a tubular metal spoke having a smaller outer end occupying the outer part of said opening and said end being bordered by a fillet fitted in the rounded inner part of said opening, said fillet and the cooperating rounded edge surface of the felloe opening being designed for limited universal pivotal motion and adapted to distribute shocks and bending strains whereby 85 to avoid fracture of the metal connection.

5. The combination specified in claim 4 in which the defining surface of the opening in the felloe is increased by an outwardly extending bordering flange.

6. In a wheel structure, the combination of a felloe provided with an opening the edge of which is rounded to increase its defining area, a hollow metal spoke formed with a filleted outer end cooperating with the rounded edge of the opening to permit a limited universal relative motion between the spoke and felloe whereby to distribute strains and means for securing the end of the spoke in the opening.

7. In a wheel structure, the combination of a felloe provided with an opening defined by an outwardly extending flange, a hollow metal spoke having a reduced outer end fitted in said opening and having a fillet 105 contacting the inner margin of the opening and means for securing the end of the spoke in the opening.

8. In a wheel, the combination of a felloe having a round hole bordered by a flange 110 and a hollow spoke fashioned with a smaller outer end inserted in said hole and having an open outer extremity enlarged across the outer margin of the felloe hole whereby to interlock the spoke and felloe.

9. In a wheel, the combination of a felloe provided with an opening defined by an outwardly projecting flange, and a hollow metal spoke projecting through said opening and having its outer extremity bent 120 across the extremity of said flange.

10. In a wheel structure, the combination of a felloe provided with an outwardly flanged opening of which an inner portion of its edge is rounded, and a tubular spoke having a smaller outer end and having adjacent thereto a fillet of progressively varying cross-sectional dimension, said outer end occupying said opening and fashioned with a spread extremity whereby to interlock the 125

parts while permitting a slight universal pivotal motion.

11. In a wheel, the combination of a felloe having circumferentially arranged holes bordered by flanges and defined by surfaces merging with the concave side of the felloe, and spokes having tubular outer ends occupying said holes and each including a sec-

tion projecting laterally and abutting one of said flanges, each of said spokes being so fashioned with a fillet defined by a longitudinally curved surface in contact with one of said merging felloe-hole-defining surfaces.

Signed by me this 21st day of June, 1921.

HERALD P. ARNT.
